(Cl. D22—2)

To all whom it may concern:

Be it known that I, Etta M. Fisher, a citizen of the United States, residing at Rochester, in the county of Monroe and State of New York, have invented a new, original, and ornamental Design for a Combined Can Opener, Bottle Opener, and Gripping Tool, of which the following is a specification, reference being had to the accompanying drawings, forming part thereof.

In the drawings:

Fig. 1 is a top plan view of a combined can opener, bottle opener, and gripping tool, showing my new design;

Fig. 2 is a side elevation thereof.

I claim:

The ornamental design for a combined can opener, bottle opener, and gripping tool, as shown.

ETTA M. FISHER.
